ABSTRACT OF THE DISCLOSURE

A seal for the partition wall between the liquid feed and the discharge tube in columns with circular flow at the contact places of the wall with the column jacket and inner tube is characterized by at least one guide piece fastened to the partition wall with a sealing tongue slidably supported therein, which is pressed by a spring to the column jacket and the inner tube.

BACKGROUND OF INVENTION

This invention relates to a seal for the partition wall between the liquid feed and the discharge pipe in columns with circular flow at the contact places of the partition wall with the column jacket and the inner tube.

In columns with circular flow, a partition wall must be located between the liquid feed and the discharge tube of each column plate. This wall serves to prevent a bypass between the liquid feed and the discharge tube, and hence to force the liquid to circulate over the column plate. For this purpose, the partition wall must fit with maximum tightness to the column jacket and the inner tube. This can be obtained easily in many cases by welding or soldering the partition wall to the column jacket. However, there are exceptions. If the material of the column jacket is very different from that of the partition wall; for example, aluminum can be welded only with difficulty, if at all. The same is true if the plates and jackets are made from different materials; for example, if the column jacket is made from steel, and the column plate and partition wall from aluminum. Such a rigid joint raises difficulties also if large differential contractions occur between the column jacket and the rectification plate, as, for example, can happen on starting the column.

SUMMARY OF INVENTION

The invention is based on the fact that in the above mentioned cases, a reliable seal is made between the partition wall and the column jacket and the inner tube.

It has been found that the partition wall between the liquid feed and the discharge tube in columns with circular flow can be sealed at the contact places of the partition wall with the column jacket and the inner tube if, according to this invention, one or two guide pieces with sealing tongues sliding in them are fastened to the partition wall, and these tongues are pressed by means of at least one spring to the column jacket and the inner tube.

THE DRAWINGS

FIG. 1 is a top view of the liquid feed and the discharge pipe of a column plate with seal according to this invention;

FIG. 2 is a sectional view along line 2—2 in FIG. 1;

FIG. 3 is a sectional view along line 3—3 in FIG. 1;

FIG. 4 is a sectional view along line 4—4 in FIG. 2;

and

FIG. 5 is a further embodiment of the sealing, according to this invention.

2

DETAILED DESCRIPTION

In the example, in FIGS. 1 to 4, the column jacket is designated with 1 and the inner tube with 2. The column plate for which the seal, according to this invention is represented, is designated by 3, under which is the column plate 4, and above plate 3, the column plate 5. For the sake of simplicity, the column plates 3, 4, 5 are represented as welded to the column jacket 1, or the inner tube 2. It is known that, especially for large-size columns, the plates are usually supported by rings or flanges. Each column plate has a liquid discharge shaft 7 leading down from any stage leading into a liquid feed chute 6 supplying the next lower stage. The column plates are arranged at a certain angle with respect to one another. The liquid feeds 6 fed by shaft 7 are substantially formed by pans or vessels 8, which are fastened, for example, with rivets 9 to the rectification plates 3, 4, 5. The tops of the pans or vessels 8 in FIG. 1 are indicated with solid and broken lines.

From the above-lying rectification plate 3, the discharge chute 10 projects into the discharge shaft 7 and vessel 8, whereby a wall of the discharge shaft 7 is formed. The discharge chute 10 is also fastened with rivets 11 to the rectification plate 3. To the upstream end of the discharge vessel 8, the partition wall 13 is fastened with rivets 12. Partition wall 13 with its sealing tongue 15, discharge chute 10, column jacket 1, and the inner tube 2 contain the discharge shaft 7.

According to this invention, the guide pieces 14 are welded to the partition wall 13, and the sealing tongues 15 are supported in them in a sliding arrangement, which are pressed by springs 16 to the column jacket 1 and the inner tube 2. The guide pieces 14 can be made from a contoured or shaped sheet metal. The spring 16 can be bent from flat or round material and is formed so that the sealing tongues 15 can be lightly pushed back when the column is assembled. The sealing tongues 15 fit with their lower edges to the rectification plate 3 and their vertical edges to the jacket and tube 2, so that a good sealing is obtained, not only with the column jacket 1 and the inner tube 2, but also with the rectification plate 3.

FIG. 5 shows a slightly different model of seal, according to this invention. In this model, the sealing tongue 15 is supported also in a sliding way in a guide piece 14, but there is only one spring 16 provided here, which presses both sealing tongues 15 to the column jacket 1 or the inner tube 2.

By the sealing according to this invention, especially small possible contractions can occur between the rectification plate and the column jacket. The mounting is simple and can be performed without any special instruments.

What is claimed is:

1. A seal for a radial partition wall between the liquid discharge shaft and the liquid feed chute in gas-liquid contacting columns having a stationary inner tube cylinder and a stationary concentric jacket cylinder and having superimposed, perforate transverse plates peripherally contiguous to said cylinders, with circular liquid flow at the contact places of the sealing tongues with the column jacket cylinder and the inner tube cylinder, characterized by guide piece means fastened to the partition wall, said sealing tongue means slidably supported in said guide piece means, and resilient means pressing said tongue means against the column jacket cylinder and the inner tube cylinder.

2. A seal as set for in claim 1 wherein said jacket cylinder and said inner tube cylinder and said partition wall are made of dissimilar materials.

3

3. A seal as set forth in claim 1 wherein said resilient means is no thicker than said tongue means.

4. A seal as set forth in claim 1 wherein said guide piece means comprises a pair of guide pieces, and said sealing tongue means comprising a tongue in each of said guide pieces.

5. A seal as set forth in claim 4 wherein said resilient means comprising a spring pressing against each tongue.

6. A seal as set forth in claim 4 wherein said resilient means comprises a single spring reacting against both of said tongues.
